UNITED STATES PATENT OFFICE.

GEORGE H. GIBSON, OF MONTCLAIR, NEW JERSEY, ASSIGNOR TO COCHRANE CORPORATION, OF PHILADELPHIA, PENNSYLVANIA, A CORPORATION OF PENNSYLVANIA.

WATER-DEAERATING APPARATUS.

Application filed December 19, 1921, Serial No. 523,545. Renewed April 11, 1924.

The general object of the present invention is to provide improved apparatus for eliminating air from water without requiring the water to be heated above a maximum temperature which is substantially below 212°, and which will permit of utilization of exhaust steam available for the purpose in restricted and variable amount, though the invention in its broader aspects is not restricted to the use of exhaust steam but may be carried out with live steam.

The invention was primarily devised for, and is of especial utility in treating boiler feed water which is to be preheated in an economizer before being passed into the boiler, and where the steam available for use is ordinarily insufficient to heat the water to a temperature of 212°.

The various features of novelty which characterize my invention are pointed out with particularity in the claims annexed to and forming a part of this specification. For a better understanding of the invention, however, and its advantages, reference should be had to the accompanying drawings and descriptive matter in which I have illustrated preferred forms of apparatus.

Of the drawings:

Fig. 1 is an elevation in section of one form of deaerating apparatus;

Fig. 2 is a diagrammatic elevation taken at right angles to Fig. 1;

Fig. 3 is a transverse section on the line 3—3 of Fig. 1;

Fig. 4 is a diagrammatic representation of a system in which the apparatus of Figs. 1, 2, and 3, is associated with a heat exchanger; and

Fig. 5 is an elevation in section of a modified form of deaerating apparatus.

In the drawings, and referring first to the construction shown in Figs. 1 to 3, A represents a scrubbing and deaerating chamber which is shown as a tank divided into upper and lower compartments A' and A", respectively, by a partition B. Mounted on the partition B is a tray box C having closed sides but open at its lower end, through an opening B' formed in the partition B, to the compartment A", and open at its upper end to the compartment A'. Mounted in the tray box C are a series of oppositely inclined trays C', such as are commonly used

in open feed water heaters. As shown each tray C' is provided adjacent its lower end with a steam inlet port C³, and the bottom of the tray is provided with ports through which the water passing onto the tray may fall in a multiplicity of relatively small streams. Each tray C is formed with flanges C² which support the tray above it at the proper angle. Mounted on top of the tray box C is a water distributing box C⁴ receiving water as hereinafter described through two supply pipes D and E. The water thus supplied to the tray box overflows along the side C⁵ of the box on to the uppermost tray C'.

Steam for scrubbing the water and freeing it from air is injected into the water in the compartment A² through a manifold F comprising, in the form shown, a main pipe extending horizontally into the chamber A² near the bottom of the latter, and numerous small lateral distributing pipes F', each of the latter being formed with a multiplicity of discharge orifices. The manifold F is located well below the normal water level in the compartment A². In addition to supplying steam to the deaerating chamber through the manifold F, steam may advantageously, though not necessarily, be introduced into the compartment A² above the water level therein, and in the apparatus shown in the drawings, steam is thus introduced into the compartment A² through an atomizer pipe G, and also through an inlet A³. The atomizer pipe G is shown as horizontally disposed below the tray box C and is formed with a plurality of small discharge orifices at one side. The water dripping from the lowermost of the trays C is carried on to the top of the atomizer pipe G by a baffle or drain board C⁶.

The steam used for scrubbing the water may be live steam or exhaust steam from any suitable or available source, but as shown this steam is supplied from an exhaust pipe H in which it is desirable to maintain a pressure above that of the atmosphere to prevent air leakage into the pipe H and into the apparatus from which this pipe leads, and for this purpose an automatic flow valve I is interposed between the pipe H and the deaerating chamber A. As shown the valve I comprises a valve body divided by

suitable partitions into an inlet chamber and two outlet chambers i and ia connected to the inlet chambers by ports I' and I^2 respectively. The ports I' , of which there are two in the construction shown, are controlled each by a corresponding valve disc I^3 . Associated with each of the valve discs I^3 is a corresponding piston I^4 working in a piston chamber I^5 which is open at its outer end to the atmosphere and is open at its inner end to the chamber i . At the outer end of each piston chamber I^5 a stop I^9 is provided limiting the outward movement of the piston. Each valve disc I^3 and corresponding piston I^4 are free to move apart to the extent necessary to permit the valve disc to seat and close the corresponding port I' while the piston is in engagement with the stop I^9 . The relative movement of approach of each valve disc I^3 and the corresponding piston I^4 is limited, however, so that a sufficient inward movement of the piston causes the valve disc to seat and close the port controlled by it. In the construction shown each valve disc I^3 is formed with a stem I^{10} which is telescopically received in a socket I^{11} carried by the corresponding piston I^4 and the movement of approach of each valve disc and the corresponding piston is limited by the engagement of the valve stem I^{10} with the bottom of the socket I^{11} . The pistons I^4 are the same diameter as the valve discs I^3 . An adjustable valve closing force is exerted on the valve discs I^3 by springs I^6 having their lower ends in engagement with the valve discs and having their upper ends engaged by a cross head I^7 which may be raised and lowered by manipulation of a threaded spindle I^8 .

In the normal condition of operation in which the pressure in the inlet chamber of the valve exceeds the pressure in the outlet chamber i , fluctuations in the pressure in the outlet chamber i , have no effect upon the movements of the valve discs I^3 controlling the ports I' , and these valve discs open and close accordingly as the pressure of the fluid in the inlet chamber of the valve exerts an opening force on the valve discs which is greater or less than the sum of the opposing forces due to the springs I^6 and to the pressure of the atmosphere acting against the outer ends of the pistons I^4 . In consequence the valve discs I^3 contracting the ports I' will open only when the pressure at which steam is supplied to the inlet chamber of the valve exceeds the pressure of the atmosphere by an amount fixed by the tension of the springs I^6 . Under this normal condition of operation the valve discs I^3 and pistons I^4 cooperate to control the ports I' exactly as they would if the valve discs I^3 were rigidly connected to the corresponding pistons I^4 . Under abnormal conditions, how-

ever, in which the pressure in the outlet chamber i exceeds that in the inlet chamber of the valve, the separable connections between the pistons I^4 and valve discs permit the latter to act as check valves and prevent back flow through the ports I' of steam or water when the pressure in the chamber A exceeds the pressure in the steam supply pipe H as may occur from time to time.

The ports I^2 are controlled by valve discs I^3 , and connections exactly similar to those described for controlling the ports I' , but in practice as hereinafter explained the springs controlling the valve discs I^3 for the ports I^2 are maintained under greater tension than are the springs pertaining to the ports I' .

The outlet chamber ia opens directly to the chamber inlet A^3 . A pipe J connects the outlet chamber i to the manifold F through a branch pipe J' and through a second branch pipe J^2 to the atomizer pipe G . Each of the branch pipes J' and J^2 is preferably provided with an individual throttle valve K , and a non-return valve L is preferably provided in the branch J' to prevent back flow of water into the chamber i , in case a vacuum occurs therein greater than the vacuum in the deaerating chamber.

The steam supply pipe J' may be connected directly to the manifold F but advantageously as shown I insert a steam ejector S in between the pipe J' and manifold. The mixing chamber S' of the ejector is connected to the interior of the tank A above the water level in the latter by a pipe T . In consequence the steam passed into the manifold F comprises not only the steam supplied to the ejector S , but also steam drawn from the chamber A and repassed through the body of water in the lower portion of the chamber A . This recirculating of steam may be interrupted when desired by closing the valve T' in the pipe T .

Air and vapor are withdrawn from the compartment A' of the deaerating chamber through the outlet A^4 located near the upper end of the compartment and connected by a pipe O^2 to the exhausting device O , which, as shown, is a steam ejector to which the impelling steam is supplied through the pipe O' . The discharge pipe O^3 from the ejector O passes into the condenser chamber N which as shown is mounted on top of the deaerating chamber A . Within the condenser the pipe O^3 is formed with an upturned portion provided with lateral discharge orifices O^4 . The condensing water is discharged into the condenser through a pipe E^5 on to a water spreader P which, as shown, is in the form of a shallow box resting on top of the upturned end of the pipe O^3 and provided with perforations in its bottom through which the water falls in fine streams down past the discharge ports O^4 . The water collecting in the bottom of the

condenser N is discharged from the latter into the trough C⁴ through the pipe E which has its upper end bent over to form a siphon, and includes a valve E'. The latter is operated by a float E² in the chamber N which opens and closes the valve as required to permit the discharge of water accumulating in the lower portion of the condenser N while preventing the free influx of air or vapor into the deaerating chamber through the pipe E.

The water supply pipe D is shown as passing through but does not open to, the condenser N so that the water passing into the deaerating chamber A through the pipe D may absorb some heat from the condenser. Water is supplied to the condenser N through the pipe E⁵, and is directly supplied to the deaerating chamber A through the pipe D in response to the accumulation of water in the compartment A² by float actuated valve mechanism adapted to insure an adequate supply of condensing water to the condenser N as well when the amount of water passing through the apparatus is relatively small, as when it is larger, and to prevent an unduly large amount of water from passing through the condenser N, when the demand is normal. For this purpose in the particular construction illustrated, separate control valve D¹⁰ and E¹⁰ are provided in the water supply supply lines D and E⁵. The valve D¹⁰ has its operating stem connected by the rod D¹¹ to the crank arm of a rock shaft projecting through the wall of the compartment A² and connected within the latter to a float DA. The operative arm of the valve E¹⁰ is similarly connected by a rod E¹¹ to the rock shaft connected to a float EA in the compartment A². The floats DA and EA are so arranged and connected to the control valves D¹⁰ and E¹⁰, that the valve D¹⁰ will be opened wide when the water in the compartment A² falls to the level 1 and will be tightly closed when the water in the compartment A' rises to or above the level 2, while the valve E¹⁰ will be wide open when the water in the compartment A² is at, or below the level 3, and will be fully closed when the water in the compartment A² rises to, or above the level 4. The controlling valve and float mechanism described is effective for accomplishing its purpose, but the same results can be obtained with a single control valve having two outlets, one to the pipes E⁵ and one to the pipe E¹⁰, and a single float movable between the levels 1 and 4.

In the contemplated operation of the apparatus shown in Figs. 1, 2, and 3 the water level in the compartment A² will lie between the levels 1 and 2 when the demand for treated water withdrawn from the apparatus through the outlet A⁶ is the average or normal demand. The valve D¹⁰ will then be wide open and the valve E¹⁰ will be partly open. With the throttle valves K both open, steam will pass into the water in the bottom of the compartment A² through the manifold F and through the atomizer G and, provided the pressure in the pipe H is high enough, steam will also pass into the compartment A² through the inlet A³. Steam should be supplied to the manifold F in such quantities that some or all of the steam will pass through the body of water in the bottom of the compartment A² and will rise from the upper surface of this water. The steam passed into and not condensed in the compartment A² eventually passes out of the compartment A² into the tray box C, and the portion of the steam not condensed therein by contact with the water running over the tray plates passes out of the tray box into the compartment A'. Vapor and air or other gases mixed with it are withdrawn from the compartment A' through the outlet A⁴ by the ejector O which discharges into the condenser N. In the condenser N practically all of the steam and vapor discharged by the ejector are condensed. The air and gases separated from the steam and vapor by condensation of the latter in the condenser N escape from the condenser to the atmosphere through the vapor outlet N'.

In the scrubbing of the water in the deaerating chamber it will be observed that the steam and water act on the counter current principle. The water entering the deaerating chamber is first scrubbed by the steam in its passage down through the tray box and then after it falls into the pool in the bottom of the compartment A². Furthermore both in the pool and in the trays separately considered, the scrubbing proceeds on the counter flow principle. In consequence the steam discharged from the manifold F comes first into contact with water containing the least air or gas and then as it travels to the outlet A⁴ is progressively in contact with water in which the air content progressively increases.

The scrubbing effect obtained by forcing steam through the water when the latter is heated approximately to its final temperature facilitates the elimination from the water of air which, under the temperature and pressure conditions prevailing in the apparatus, is no longer held in solution in the water, but is mechanically entrained therein. Such scrubbing I have found is practically essential in commercial apparatus to secure a reasonably rapid rate of deaeration under moderate temperature and vacuum conditions. The recirculation of the steam which may be obtained by the use of the injector S augments the scrubbing action obtainable with a given amount of steam. When the temperature of the water

is relatively low and the vacuum correspondingly high, as conditions of operation make necessary in practice from time to time, it is apparently more difficult to remove the air from the water than when the temperature of the water is higher and the vacuum lower. This is due, I believe, to the fact that at the high vacuum a given weight of air occupies a larger volume than at the lower vacuum and forms a greater number of air bubbles. The higher vacuum tends, moreover, to increase the air infiltration through the shell of the heater and the pipe connections. The use of the preferential valve mechanism described insures an effective utilization of all the exhaust steam available for deaerating and heating the water, and my invention, in the form disclosed, in Figs. 1, 2 and 3, is a highly advantageous one where the exhaust steam is available in restricted amounts which vary independently of the volumetric demand for deaerated water.

Where exhaust steam is available at all times in amounts equal to, or in excess of, the requirements for deaerating and heating the water treated, or where live steam is employed, the steam supply connections to the deaerating apparatus require no control valves, at least none other than ordinary throttle or stop valves, unless as in supplying water to economizers, the temperature at which the water leaving the deaerating apparatus should be kept approximately constant at some value appreciably below 212° F. In any case, however, to avoid water hammer in starting the apparatus into operation, or in increasing the temperature maintained in the deaerating chamber, I may advantageously provide a special switch valve mechanism as shown in Fig. 4 for passing all of the steam into the deaerating chamber above the body of liquid therein until the water in the deaerating chamber is raised to the temperature of the steam introduced into the chamber, after which all, or the desired portion, of the steam for deaerating and heating the water may be introduced through the scrubbing pipe in the bottom of the deaerating chamber.

In Fig. 4 the valve I in Figs. 1 and 3 is replaced by a switch valve IA having one valve seated outlet I¹⁰ connected to the heater inlet A³, and another outlet I¹¹ connected to the pipe J. A movable valve member I¹² is provided with an operating handle I¹³ by means of which the valve member may be adjusted to close or throttle either of the outlets I¹⁰ and I¹¹, or to throttle both as may be desired.

Where it is desirable, as in supplying water to a low temperature economizer section, to reduce the final delivery temperature of the water below that maintained in the deaerating chamber and at the same

time minimize the heat requirements of the deaerating apparatus, I may advantageously use a heat exchanger as shown in Fig. 4 to transfer heat from the water leaving the deaerating chamber to the water passing to the deaerating chamber for treatment therein. As shown in Fig. 4 the heat exchanger Q is of the tubular type and comprises tubes Q² through which the water leaving the deaerating chamber passes from the outlet A⁵. After passing through the tubes Q² the water passes away from the heat exchanger to the place of use through the exchanger outlet Q'. The water to be treated passes into the intertube space of the heat exchanger through a supply connection R and is delivered from this space to the supply pipe D. In the modified form of my invention shown in Fig. 5, the deaerating chamber AA employed, is provided in its upper portion with a series of trays CA on to which water is discharged from the main water supply pipe D and from the outlet E²¹ from the condenser N. Steam is normally introduced into the deaerating chamber AA only through the manifold F and provisions are made for recirculating steam through the body of water in the lower portion of the deaerating chamber. For this purpose the inlet to the manifold F is connected to the outlet of an ejector S supplied with live or exhaust steam through the supply pipe HA. The mixing chamber of the ejector S is connected by a pipe T to the chamber AA above the water level in the latter as in Fig. 1. Steam is also supplied to the air ejector O from the steam supply main HA.

In Fig. 5 a single float DE is connected by links D¹⁵ and E¹⁵ to the operating arms of the valve D¹⁰ and E¹⁰, and by providing a pin and slot connection as shown between the float DE and the link D¹⁵ it is possible to cause the valves D¹⁰ and E¹⁰ to open and close in response to the same variations in water level as bring about the opening and closing movements of these valves in the construction shown in Figs. 1 and 2. By closing the valve K' and valve K² steam may be passed into the upper portion of the deaerating chamber AA as required to heat the latter up in starting, or when the temperature in the deaerating chamber is to be increased without causing the water hammer which might result from the introduction of steam into the deaerating chamber through the manifold F at such times.

No claim is made herein to the combination with the deaerating apparatus of a heat exchanger as this combination is disclosed and claimed in my prior application, Serial No. 411,232, filed September 18, 1920, and no claim is made herein on the switch valve mechanism shown in Fig. 5 as that mechanism is disclosed and claimed in my co-pending application, Serial No. 523,546

filed of even date herewith. Certain other novel features of construction and arrangement disclosed but not claimed herein are also disclosed in my co-pending application, 5 Serial No. 523,547 filed of even date herewith, and in my prior application Serial No. 460,389, filed April 11, 1921.

While in accordance with the provisions of the statutes I have illustrated and described the best forms of my invention now known to me, it will be apparent to those skilled in the art that changes may be made in the forms of the invention disclosed without departing from the spirit of my 15 invention as set forth in the appended claims, and that certain features of my invention may sometimes be used to advantage without a corresponding use of other features.

20 Having now described my invention, what I claim as new and desire to secure by Letters Patent, is:

1. Apparatus for deaerating water comprising a closed chamber with air and water outlets, means for supplying water to the chamber at an upper level in amounts as required to maintain a body of water in the chamber filling the latter to an approximately constant level below said upper level, 25 and means for supplying steam to the chamber comprising a lower steam inlet opening to the chamber below the water level therein and an upper steam inlet opening to the chamber above said water level and a selective valve mechanism responsive to the pressure of the steam supplied and operative to cause all the steam supplied to the chamber to enter the latter through said lower inlet when the steam supply pressure 30 is below a certain value and to cause steam to enter the chamber through both inlets when the steam supply is at a higher pressure.

2. Apparatus for deaerating and heating water comprising in combination a closed heating and deaerating chamber provided with air and water outlets and with a water spreader in its upper portion, means for introducing water into the chamber over said water spreader in amounts as required to maintain a body of water in the lower portion of said chamber the level of which is below said spreader, means for injecting steam into the body of water, means for injecting steam in jets into said chamber below said spreader and above said body of water, and means for causing the water to flow in a film-like stream across the paths of said steam jets.

3. Apparatus for deaerating and heating water comprising in combination a closed heating and deaerating chamber provided with a water spreader in its upper portion and having air and water outlets, means for supplying water to said chamber over said

spreader and in amounts as required to maintain a body of water in the lower portion of the chamber below said spreader, means for discharging steam into the body of water, means for discharging jets of steam across the path of the water falling from said spreader into said body of water, and separate means for supplying steam to the chamber above said body of water, all of said steam supplying means receiving steam from a common source, and means responsive to the pressure at which steam is supplied from said source for preventing steam from entering the chamber through the last mentioned inlet except when the pressure at which the steam is supplied exceeds a predetermined value.

4. Apparatus for heating and deaerating water comprising in combination a closed heating and deaerating chamber, a jet condenser, a steam jet exhaust for withdrawing air and vapor from said chamber and delivering it to said jet condenser, a water discharge from the condenser into said chamber, a water supply connection to the condenser, a separate water supply connection to the chamber, means responsive to the amount of water in the chamber regulating the water supplied to the condenser and to the condenser through the separate water supply connection to the latter as required to maintain an approximately constant water level in the chamber and operative to cut off the separate supply of water to the chamber before interrupting the supply of water to the condenser as the water level in the chamber approaches a desired maximum, and means for supplying steam to said chamber.

5. Apparatus for heating and deaerating water comprising in combination a closed chamber having a water outlet and an air outlet, means for supplying water to be deaerated to said chamber to maintain a body of water therein partially filling the chamber, and means for scrubbing said water with steam including a steam ejector having its outlet connected to said chamber below the water level therein and having its mixing chamber connected to the first mentioned chamber above the water level in the latter and means for supplying steam to the inlet of said ejector.

6. Apparatus for deaerating and heating water comprising in combination a closed heating and deaerating chamber divided into upper and lower compartments, a conduit connecting said compartments, a set of water spreading trays or baffles in said conduit, means for introducing water into the lower compartment through said conduit in amounts as required to maintain a body of water in the lower portion of said compartment the level of which is below said conduit, means for atomizing the water leaving

ing said conduit, means for discharging air from the upper compartment, and a water outlet from the lower compartment.

7. Apparatus for deaerating and heating water comprising in combination a closed heating and deaerating chamber divided into upper and lower compartments, a conduit connecting said compartments, a set of water spreading trays or baffles in said conduit, means for introducing water into the lower compartment through said conduit in amounts as required to maintain a body of water in the lower portion of said compartment the level of which is below said conduit, means for injecting steam into the body of water, a steam jet atomizer located between said conduit and said body of water and adapted to discharge steam jets across the path of the water leaving said conduit, means for discharging air from the upper compartment, and a water outlet from the lower compartment.

8. Apparatus for heating and deaerating water comprising in combination a closed heating and deaerating chamber divided into upper and lower compartments having communication with one another for the passage of water from the upper compartment into the lower compartment and for the passage of steam from the lower compartment into the upper compartment, means for introducing water into the upper compartment as required to maintain a body of water partially filling the lower compartment, means for discharging air from the upper compartment, a water outlet from the lower compartment, means including a main steam supply connection to the lower compartment for therein scrubbing the water entering the latter with steam, means in the upper compartment for subjecting the water passing through the latter to the scrubbing action of the steam entering the upper compartment from the lower compartment, and a separate steam supply connection (for subjecting the water to a local heating action as it passes from the upper compartment into the lower chamber.)

9. Apparatus for heating and deaerating water comprising in combination upper and lower compartments having communicating provisions permitting the passage of water from the upper compartment into the lower

compartment and the passage of steam from the lower compartment into the upper compartment but normally ineffective to pass steam or air from the upper compartment into the lower compartment, means for introducing water to be heated and deaerated into the upper compartment, means for discharging air from the upper compartment, a water outlet from the lower compartment, means including a main steam supply connection to the lower compartment for therein scrubbing the water with the major portion of the steam supplied to the apparatus, means for subjecting the water while in the upper compartment to the scrubbing action of the steam entering the upper compartment from the lower compartment, and means including a separate steam supply connection for effecting an intimate contact of the water with steam as the water passes from the upper compartment into the lower compartment.

10. Apparatus for heating and deaerating water comprising in combination upper and lower compartments having communicating provisions permitting the passage of water from the upper compartment into the lower compartment and the passage of steam from the lower compartment into the upper compartment but normally ineffective to pass steam or air from the upper compartment into the lower compartment, means for introducing water to be heated and deaerated into the upper compartment, means for discharging air from the upper compartment, a water outlet from the lower compartment, means including a main steam supply connection to the lower compartment for therein scrubbing the water with the major portion of the steam supplied to the apparatus, means for subjecting the water while in the upper compartment to the scrubbing action of the steam entering the upper compartment from the lower compartment, and means including a separate steam supply connection for subjecting the water to a local steam jet action as the water passes from the upper compartment into the lower compartment.

Signed at Philadelphia in the county of Philadelphia and State of Pennsylvania this sixteenth day of December A. D. 1921.

GEORGE H. GIBSON.
